UNITED STATES PATENT OFFICE.

WILLIAM WALKER STRONG, OF MECHANICSBURG, PENNSYLVANIA.

PROCESS AND APPARATUS FOR PRECIPITATING MATTER FROM GASES.

1,325,124.

Specification of Letters Patent. Patented Dec. 16, 1919.

Application filed October 23, 1918. Serial No. 259,303.

To all whom it may concern:

Be it known that I, WILLIAM WALKER STRONG, a citizen of the United States, residing at Mechanicsburg, county of Cumberland, and State of Pennsylvania, have invented certain new and useful Improvements in Processes and Apparatus for Precipitating Matter from Gases, of which the following is a specification.

10 My invention relates to improvements in process and apparatus for precipitating matter from gases, and it consists in the steps hereinafter described, and the means used in carrying out these steps.

15 An object of my invention is to provide a process by means of which poisonous fumes, smoke, or other matter suspended in the air, or light gaseous body, may be precipitated and removed from the air, or other gaseous

20 body.

A further object of my invention is to provide an electrical device for the removal of suspended particles of matter by ionizing or electrifying said particles.

25 A further object of my invention is to provide an ionizing device to be used in connection with an absorbent, such as charcoal, or the like, for increasing the absorptive power of the latter.

30 A further object of my invention is to provide an ionizing device which requires a relatively small voltage to operate it, as compared with the amount of matter ionized.

Other objects and advantages will appear 35 in the following specification, and the novel features of the device will be particularly pointed out in the appended claims.

40 My invention is illustrated in the accompanying drawings, forming part of this application, in which—

Figure 1 is a diagrammatic view of an induction coil connected up with one form of the ionizing device, the latter being shown in section;

45 Fig. 2 is a detailed view of a modified means of supporting the active electrodes;

Fig. 3 is a sectional view of a portion of a modified form of the device;

Fig. 4 is a sectional view of a portion of 50 another modified form; and

Fig. 5 is a transverse sectional view showing another modified form.

The precipitation of suspended matter in gases by the use of electric discharges has, 55 as far as I am aware, been accomplished by

the use of relatively great voltage. One reason for this is that in the devices hitherto proposed the active electrode is immediately surrounded by an insulator in the very part of the electric field where the greatest ionizing effect should take place, as for instance, in the patents to Hardie, 768,450, and Blake, 913,941. Moreover, these devices are primarily designed for stationary plants, while in the present invention one of the objects is 60 to provide an ionizing apparatus which is portable, and which may be carried by a soldier, a fireman, or any one else who is liable to suffer injury from breathing noxious fumes. A portable apparatus necessarily requires a light weight device for generating a relatively low voltage which voltage, however, must be sufficient to cause an electric discharge which will insure the precipitation of the noxious matter. 75

In carrying out my invention I make use of a battery 1 which is connected with an induction coil having a primary wire 2, a secondary 3, a condenser 4, and an interrupter 5 for the primary circuit, this induction coil being of the ordinary "buzzer" type. 80

For the active electrode of the ionizer, I may make use of a small wire 6, which is disposed in the center of a tube 7 which 85 serves as a dielectric, being made of glass or other suitable material. In the form shown in Fig. 1, the tube is provided with end closures 8 and 9 respectively, and the wire 6 is normally under the tension of a 90 spring to keep the wire straight. On the outside of the tube 7 is wound a wire 11, one terminal of the secondary 3 of the induction coil being connected to the wire 6, and the other to the wire 11. The tube 7 has an 95 inlet 12, and an outlet 13, the arrows indicating the direction of flow of the gas through the tube.

With an apparatus set up as shown in Fig. 1, the electric discharge ionizes the 100 matter carried by the gas in its passage from the inlet 12 to the outlet 13, and causes the precipitation of the matter on the wire 6, as well as on the walls of the tube 7. When such a device is used in connection with the 105 gas mask, such as that in use by soldiers, the outlet 13 is connected to the mask (not shown) and the noxious fumes are precipitated before entering the same.

Associated with the gas masks which are 110

in ordinary use today, are devices for absorbing certain fumes and noxious matter, such absorbents as charcoal, and the like being largely employed. Now the ionization, 5 which is accomplished by my device, tends to considerably increase the absorptive power of these agents. In Fig. 3 I have shown a portion of a modified form of the device in which absorbent material, such as 10 charcoal, is made use of, this absorbent material being shown at 14. Where an electric discharge takes place in a tube, such as that shown in Fig. 3, the "electric wind" produced greatly increases the absorption of 15 gases. Consider the case of a gas containing oxides of nitrogen that are to be absorbed: If these gases are passed over charcoal in the absence of an electrical discharge, the oxides of nitrogen will be absorbed as dif- 20 fusion brings them into contact with the charcoal surface. Subject the gases to the action of the "electric wind" and the rate of absorption will be greatly increased. It has been found by experiment that the rate 25 of absorption can be increased 40%.

In the case of gas masks for soldiers, it has been found that not all of the noxious fumes are absorbed. With the use of the electric precipitating device certain fumes 30 which would be unaffected by the ordinary gas mask, will be precipitated. The use of an electrical precipitating device, furthermore, obviates the necessity of the use of a large quantity of absorbent by increasing the 35 absorbing power. This is a decided advantage, since any absorbent tends to increase the difficulty of breathing and there is a limit to the amount of absorbent that can be used.

40 In Fig. 2, I have shown a modified form of the device in which the active electrode 6^a is coiled around a support 15, in this case a glass tube. I find that this provides a means of keeping a small wire in position 45 very easily.

In Fig. 4, I have shown a further modified form in which the active electrode 6^a is supported by a tube 15, while the passive electrode 16 is on the exterior of an insulating tube or dielectric 17. The absorbent material 18, which in this instance may consist of moist soda lime for the absorption of 50 oxides of nitrogen, is held in position by the use of a netting 19 such as cloth mosquito netting.

55 In Fig. 5, I have shown a further modified form in which the active electrode 9^x is surrounded by passive electrodes 19, each insulated by tubes 20. Absorbent material, 60 such as charcoal 21, may be placed between the active electrode 9 and the tubes 20, containing the passive electrodes 19.

It will be observed that in each of the 65 forms shown the active electrode has a relatively great curvature. The distinction be-

tween the active and passive electrodes lies in the fact that the active electrode surface has this great curvature, while the curvature of the passive electrodes is made as small as convenient, and furthermore that the 70 ionization takes place at the surface of the active electrode. Where the curvature of the surface is greater, less potential is required to "break down" the gas, or to cause a discharge.

If the electric discharge takes place in a closed vessel, it will be found that the "electric wind" causes an increase in the pressure of the gas in which it takes place. In the case where the electrodes consist of a wire 80 in a metallic pipe, this "electric wind" pressure is often called the corona pressure. In the production of chemical compounds, and the precipitation of fumes by means of the electrical discharge, it is found that the 85 magnitude of these results is proportional to the corona pressure, and that this pressure can be taken as a measure of the action of the electrical discharge.

I am aware that devices of the type described above have been used for ozonizing air. The present device, however, is not intended for such use, and on the other hand, the ozonizing of the air is a positive disadvantage as, for instance, in the case of the 85 use of gas masks, where ozone would produce an irritating effect. As far as I am aware, the precipitation of noxious fumes or other matter, from gases by an electric discharge in the immediate vicinity of an 100 active, uninsulated electrode, has never been done, at comparatively low voltages.

Various modifications of the device might be made without departing in the least from the spirit and scope of the present invention.

I claim:

1. A gaseous ionizing device, comprising an active electrode in contact with the gas, an absorbent element in the field of the active electrode and in contact with the gas, 110 and a passive electrode out of contact with the gas.

2. An apparatus for precipitating matter from gases, comprising an active electrode in contact with the gas, and having a relatively great surface curvature, and a passive electrode out of contact with the gas, 115 and having a comparatively small surface curvature.

3. An apparatus for precipitating matter 120 from gases comprising an active electrode in contact with the gas and having a relatively great surface curvature, a passive electrode out of contact with the gas and having a comparatively small surface curvature, and a supporting dielectric between said active and said passive electrodes.

4. The herein described process of precipitating matter from gases which consists in bringing said gases into immediate con- 130

tact with an active electrode, in the presence of an absorbent element, and in causing an electric discharge from said electrode.

5. The herein described process of precipitating matter from gases which consists in passing a stream of gas into immediate contact with an active electrode and an absorbent element, and in causing an electric discharge from said electrode through the 10 path of the stream of gas and in the immediate presence of the absorbent element.

6. The herein described steps in a process of precipitating matter from gases, which consists in passing a stream of gas into immediate contact with an absorbent, and in 15 simultaneously ionizing the gas.

7. An apparatus for precipitating matter

from gases comprising an active electrode in contact with the gas, having a relatively 20 great surface curvature, a passive electrode out of contact with the gas and having a comparatively small surface curvature, a supporting dielectric between said active and said passive electrodes, and means for 25 charging said electrodes from a source of electricity of relatively low potential whereby matter in the gas is precipitated.

8. The herein described step in a process of precipitating matter from gases, which 30 consists in augmenting the absorptive power of a gas absorbing material by placing the latter in the field of an electric discharge during the passage of gas past the absorbent.

WILLIAM WALKER STRONG.
